UNITED STATES PATENT OFFICE.

ANNA K. MAY, OF PHILADELPHIA, PENNSYLVANIA, ASSIGNOR TO WILLIAM H. McCALLUM AND IRVING McCALLUM, OF SAME PLACE.

DESIGN FOR CARPET FOR TROLLEY-CAR SEATS.

SPECIFICATION forming part of Design No. 31,879, dated November 21, 1899.

Application filed October 26, 1899. Serial No. 734,885. Term of patent 3½ years.

To all whom it may concern:

Be it known that I, ANNA K. MAY, a citizen of the United States, residing at the city of Philadelphia, in the county of Philadelphia and State of Pennsylvania, have invented and produced a new and original Design for a Carpet for a Trolley-Car Seat, of which the following is a specification, reference being had to the accompanying drawing, forming part thereof.

The leading feature of my design consists of two oblong panels each well covered with ornamental figures and each bounded on its four sides by an ornamental border.

In the drawing, 1 and 2 are panels which are shown as if their center portions were broken away in order to get them on the

sheet. Each of these panels is oblong, and it is well covered with an Oriental figure or pattern. Around the four edges of each panel is arranged a border 3, into which the pattern breaks, and inclosing the border 3 there is lattice-work 4.

Having described my invention, what I claim as new, and desire to secure by Letters Patent, is—

The design for a carpet for a trolley-carseat, substantially as shown and described.

In testimony whereof I have hereunto signed my name.

ANNA K. MAY.

In presence of—

GRACE B. HURLBUT,
W. J. JACKSON.
